DESIGN FOR A REFLECTOR-EQUIPPED LIFE PRESERVER

Raymond S. Smuland, Duluth, Minn.

Application September 4, 1941, Serial No. 103,157

Term of patent 3½ years

To all whom it may concern:

Be it known that I, Raymond S. Smuland, a citizen of the United States, residing at Duluth, in the county of St. Louis and State of Minnesota, have invented a new, original, and ornamental Design for a Reflector-Equipped Life Preserver, of which the following is a specification, reference being had to the accompanying drawing, forming part thereof.

Figure 1 is a front perspective view of a reflector-equipped life preserver, showing my new design.

Figure 2 is a rear perspective view thereof.

I claim:

The ornamental design for a reflector-equipped life preserver, as shown.

RAYMOND S. SMULAND.
